UNITED STATES PATENT OFFICE.

CHARLES Y. JONES, OF SAXTON, PENNSYLVANIA.

DESIGN FOR A THIMBLE.

Application filed November 9, 1927 Serial No. 24,048. Term of patent 7 years.

To all whom it may concern:

Be it known that I, CHARLES Y. JONES, a citizen of the United States, residing at Saxton, in the county of Bedford and State of Pennsylvania, have invented a new, original, and ornamental Design for a Thimble, of which the following is a specification, reference being had to the accompanying drawings, forming part thereof.

I claim:

The ornamental design for a thimble, as shown.

CHARLES Y. JONES.
